UNITED STATES PATENT OFFICE.

JOSEPH C. BECKLEY, OF DAYTON, OHIO.

WATER-TUBE BOILER.

No. 821,329.

Specification of Letters Patent.

Patented May 22, 1906.

Application filed February 10, 1906. Serial No. 300,519.

To all whom it may concern:

Be it known that I, JOSEPH C. BECKLEY, a citizen of the United States, residing at Dayton, in the county of Montgomery and State of Ohio, have invented certain new and useful Improvements in Upright Water-Tube Boilers; and I do declare the following to be a full, clear, and exact description of the invention, such as will enable others skilled in the art to which it appertains to make and use the same, reference being had to the accompanying drawings, and to the figures of reference marked thereon, which form a part of this specification.

15 This invention relates to improvements in upright water-tube boilers.

The objects of the invention are to make an internal-firing boiler with certain well-defined advantages, hereinafter described. By 20 the term "internal firing" I mean a boiler in which the fire-box is inclosed throughout its sides and top by a water-chamber, so that the gases or products of combustion pass from the upper end of the fire-box out 25 through a fire-tube, coming in contact with said water-tubes on all sides, and thence extending upwardly around the sides of a steam-drum to superheat the steam therein. A portion of the circulating-tubes are deflected 30 inwardly from a perpendicular line to baffle or deflect the heat rising from the fire-box. The heat heretofore lost in this type of boilers by being permitted to escape directly from the fire-box to the outlet-flue is thus utilized 35 in the present case to add further heat to the water-tubes after it leaves the fire-box and finally to superheat the steam in the drum and make it dry. The result is that a more rapid and thorough generation of heat is obtained and a greater amount of the heat from 40 the fire-box is utilized. The casing is detachable from the water-leg to gain access to the water-tubes or steam-drum, and the necessity of bricking up the water-tubes, as is 45 commonly the case in water-tube boilers, is avoided, and a further advantage due to the present improvements is that the boiler may be either portable or stationary.

50 Preceding a detail description of the invention reference is made to the accompanying drawings, of which—

Figure 1 is a vertical elevation of my improved water-tube boiler with a portion of the casing broken away and a portion of the 55 water-tubes and the steam-drum and other

parts appearing in section. Fig. 2 is an enlarged diagram showing the arrangement of the tubes on the line *xx* of Fig. 1.

In a detail description of the invention similar reference characters indicate corresponding parts.

1 designates the fire-box, surrounded by a water-leg 2, which increases in area in its upper terminal and projects a substantial distance above the fire-box, as at 3, thereby reducing the heat-passage from the fire-box. Mounted upon the water-leg is a casing composed of sections 4, 5, 6, and 7 and terminating at its upper end in a cone 8, forming the outlet-flue. These sections are united at 70 their adjacent ends in a manner to permit of their detachment in order to gain access to the interior of the casing. The lower section 4 of said casing flares outwardly from the upper end of the water-leg to increase 75 the area of space throughout the length of the casing. It will be observed that the volume of water within the space inclosing the sides of the fire-box is considerably reduced in thickness as compared with the width of 80 the water-leg above the sides of the fire-box. Therefore it will be seen that the water within this reduced portion of the water-leg will be caused to heat more rapidly, and the result is that a more rapid precipitation of the mineral 85 or solid matter held in suspension will take place. Such precipitated matter is conveniently removed from the water-leg by means of a series of hand-holes at the extremity of the water-leg, which are accessible by means 90 of covers 9, and an upper series of hand-holes, also closed by means of covers 9. A greater percentage of such matter is prevented from entering the water-tubes from the water-leg, and the common annoyance due to the formation of incrustation on the interior of the 95 water-tubes is prevented.

Connected with and extending upwardly from the water-leg is a series of water-tubes 12, which are connected at their upper ends 100 to a steam-drum 13, arranged at the top of the casing and having its top or head 14 braced with a suitable number of stays 15. The head of this steam-drum is provided with a manhole and cover 16 to permit access 105 thereto. The water-tubes 12 so interposed between the water-leg and the steam-drum are arranged in inner and outer rows. The tubes of the outer rows and some of those of the innermost row extend in a per- 110

pendicular manner, while some of the tubes of the innermost row slant inwardly toward the center of the steam-drum and connect with said steam-drum at points inwardly 5 from the points of connections between said slanting tubes and the water-leg. By thus inclining a desirable number of said tubes effective means is provided for baffling the heat and causing said heat to disperse in a 10 manner to effectually spread over the surface of the tubes. Suspended from the bottom of the steam-drum 13 in a central position is a deflecting plate or shield 17, which lies a suitable distance above the entrance from the 15 fire-box. This deflecting-plate 17 is suspended by means of a rod 18, and the purpose of such plate is to prevent the heat or fire from traveling up the center of the assembled tubes. The heat or flames striking this 20 plate as they emerge from the fire-box will be deflected laterally onto the tubes and will practically assume a course as indicated by the arrows, Fig. 1. The fire and gases thus passing throughout the assembled tubes are 25 baffled in their passage to the steam-drum 13 by the inclined tubes and striking the bottom of the steam-drum are deflected outwardly between the sides of said steam-drum and the surrounding casing, from whence it escapes 30 through the outlet-flue after a maximum amount of the heat has been utilized. As before stated, the casing constructed of the united sections is detachable without disturbing the arrangement of the water-leg, 35 tubes, or steam-drum, and the necessity of bricking up the water-tubes, as is commonly done in upright-boiler tubes, is avoided.

Means are provided for thoroughly and quickly cleansing the water-tubes of the ac- 40 cumulation of soot. These means consist of a circular pipe 11, arranged immediately above the water-leg and surrounding the base of the water-tubes. This circular pipe 11 has a multiplicity of small holes 45 throughout its circular form and in positions to emit small jets of steam onto the base of the water-tubes and to thus remove the soot. The pipe 11 is connected to the steam- 50 drum 13 by an upright pipe 20, which is controlled by a valve 21 and by means of which the steam is admitted to the pipe 11 for the purposes specified.

Having described my invention, I claim—

1. In an upright water-tube boiler, a fire- 55 box, a water-leg surrounding said fire-box and projecting inwardly above the sides of said fire-box, a cylindrical casing in sections mounted upon said water-leg, a steam-drum in the upper portion of said casing, a series of 60 perpendicular water-tubes connecting the water-leg and the steam-drum, and a series of inclined water-tubes connecting the water-leg and steam-drum at points inwardly

from the points of connection of the perpendicular tubes with said steam-drum. 65

2. In an upright water-tube boiler, a fire-box, a water-leg surrounding the sides of said fire-box and projecting inwardly at the top of the fire-box, said water-leg having a greater transverse area of space above the 70 fire-box, a steam-drum, a series of perpendicular water-tubes connecting the water-leg with the steam-drum, a series of inclined water-tubes forming communications between the inner portion of the water-leg and the 75 middle portion of the steam-drum, and a cleansing device consisting of a circular jet-pipe surrounding the base of the water-tubes, and a connection between the steam-drum and said jet-pipe. 80

3. In an upright water-tube boiler, a fire-box, a water-leg inclosing the sides of said fire-box and having its upper end increased in area and extending inwardly above the top of the fire-box and surrounding the space 85 leading from the fire-box, a cylindrical casing mounted upon said water-leg, a steam-drum located at the upper end of said casing, a plurality of water-tubes connecting said water-leg with the steam-drum, the outer rows of 90 said water-tubes and a portion of the innermost row of said water-tubes extending in perpendicular positions, and a portion of the innermost row of tubes extending in inclinations and connecting with the steam-drum at 95 points inwardly from the connections thereof with the water-leg, a jet-pipe surrounding said water-tubes at the points of their connections with the water-leg, and a pipe connecting said jet-pipe with the steam-drum. 100

4. In an upright water-tube boiler, a fire-box, a water-leg inclosing the sides of said fire-box, the upper portion of said water-leg being increased in area to extend inwardly above the top of the fire-box and reduce the 105 space leading from the fire-box, a cylindrical casing mounted upon said water-leg, a steam-drum in the upper portion of said casing near the outlet-flue in the top of said casing, a plurality of water-tubes connecting said water-leg with the steam-drum, portions of said tubes extending perpendicularly, and a portion of said tubes extending in inclinations and connecting with the steam-drum at 110 points inwardly from the connections of the perpendicular pipes therewith, a deflecting-plate suspended centrally above the fire-box, and a jet-pipe inclosing the base of the water-tubes and having a connection with the steam-drum. 115

In testimony whereof I affix my signature in presence of two witnesses.

JOSEPH C. BECKLEY.
